RUDOLPH T. KELLER, OF FLUSHING, NEW YORK

METALLIC LETTERS

Application filed August 14, 1929. Serial No. 385,720.

The invention relates to the art of forming letters and numerals for signs; the letters being attractive in character and durable in construction may be made as artistic as those 5 now cut and formed of sheet metal, while comparatively cheaper in cost.

More particularly the invention relates to an improvement in letters per se, whereby not only letters and numerals of one style but 10 of many, whether they are molded, die cast or pressed, then applied to any given back or base board.

The prime object of my invention is to provide any letter of the alphabet or numeral 15 of suitable metal, such as aluminum, brass, bronze or other such material that is light and easily worked. Each letter and numeral may be provided with suitable fastening, cast integral therewith, whereby they may be 20 affixed to the sign board with the least possible trouble. These letters and numerals form a very simple, effective, as well as durable sign of any given size.

My invention will be better understood 25 from the following description taken in connection with the accompanying drawings, wherein is shown the preferred form. The drawings illustrate merely some examples of means for putting my invention into practice, 30 and its scope will be pointed out in the appended claim.

Further objects and advantages will become apparent as the description of the invention is hereinafter developed.

In the drawings, Fig. 1 is a face view of a 35 cast letter ready to be applied to a sign; Fig. 2 is an enlarged section taken on the line 2-2 of Fig. 1; Fig. 3 is a modification of a letter; Fig. 4 is another modified form 40 of a character; Fig. 5 shows how a lamp may be applied within the walls of the same; Fig. 6 is still another modified form, and Fig. 7 is a sectional view of a pressed metal letter.

Referring to Fig. 1, the object of my invention is to provide a character 10 of any suitable size that will be ready to apply to the sign board 11. The letter, as noted, will be of aluminum or any desired metal or formed by being cast or pressed of any composition 50 or formed of sheet material as may be de-

sired; the preferred form of the character is of the trough type shown, wherein the walls 12, 13, 14 and 15 are all beveled. The apices 16 of the walls may have a small flat face as shown, while the base of the walls of the cast 55 letters have a suitable number of bolts 17 placed therein while the material is plastic and preferably threaded to receive a nut 18 for securing it to the sign board 11, or to be embedded in a wall. The principal reason for having the walls more or less tapered is that the pattern may be removed with less liability than with straight walls. Again, the various characters may be molded, die cast or 60 pressed, as shown in Fig. 7.

It will be readily seen how simple it will be to apply any given number of characters to a sign board, and how easily and securely they may be attached. The trough type letter or figure is the desired style of letter, as 70 it lends itself to such a varied number of combinations for ornamental or lighting effects. First, with the letters and numerals thus cast, they form indestructible characters; second, the space 19 at the bottom between the walls permits of the usual bulb socket for sign lamps being applied in the characters without interfering in any manner with the characters themselves; thirdly, the style of the character lends themselves to the 75 neon tube method of illuminated signs, should the same be desired; fourth, the characters being cast or pressed metal, may be used and reused any number of times. While lastly, any part of a sign made with these 80 detachable characters may be altered, changed or varied in any of the several ways without destroying the sign, as would be the case with the sheet metal signs as made today.

Thus it will be seen with my improved characters they may be used with or without illumination at a very substantial reduction in the cost and provide a sign that is very attractive and not readily given to blurring out 85 in time.

Referring now to Figs. 3 and 4, it will be seen that the characters 10 or numerals may be cast, molded or pressed, either in the plain, fancy or ornamental styles, or they may have 90 that rounded effect that is so often preferred.

Each of the various styles will have suitable means for affixing them to the base.

As shown in Fig. 5, the characters forming the sign are placed in desired relationship; ⁵ then if it is desired to illuminate the same, all that is necessary is to bore the desired number of holes 20 to accommodate the bulb sockets 21 for attaching the bulbs 22 thereto, as shown. The wiring is hidden behind the sign board 11. The socket nor wiring interfering in any manner with the characters, but does cooperate with them to make an attractive sign.

In Fig. 6 another modified form of character is used. This trough character 10 has a web 23 connecting the inner walls 24 of the character, so that it becomes a semi-solid character and makes a very attractive appearance when placed on a sign, and adapts ¹⁵ to the same for the neon light or for attractive painting in the channel.

The style of character herein shown makes a very desirable display character when used alone, and when used with the tube or neon ²⁵ light is further attractive by reason of the base and side walls, which when painted on the inner parts stands out and attracts attention. In either case this style of letter will add to a sign displaying the same, as it may ³⁰ be decorated to advantage. As before noted, all elements of an highly artistic sign with only about one-half the expense that it costs now with the method now in use. Signs may be made up of one or more styles of letters ³⁵ as may be desired.

It is very desirable to provide cast or pressed metallic letters for signs, and for advertising purposes in general of such material that they will be durable in all kinds of ⁴⁰ weather and to have the same easily applied, so that it becomes only a matter of designating the style and size of the characters to be furnished. The numerals or other characters forming the advertisement each character ⁴⁵ have their own means for attachment, which as has been cited, does not require experienced labor to apply the same. Any ordinary person could apply the various characters in line, thus materially reducing the expenses of preparing such advertisement. Then, should it be desired to paint or decorate the same, it would not require that experienced sign painter, as any ordinary man may ⁵⁰ paint and otherwise decorate a sign according to given instructions from headquarters, as is now usually done.

As shown in Fig. 7, wherein the letter is made into its proper shape by being pressed ⁶⁰ from a single piece of any desired metal. Letters thus formed may be sent by parcel post in any direction, for application to any size sign board, which may or may not be painted after, as may be desired. Again, the ⁶⁵ pressed letter may have desirable advantages

under some circumstances, and may be preferred to the cast letters.

I prefer to make the outer walls 25 straight, while the inner walls 26 are inclined, the lower web 27 is preferably located a slight ⁷⁰ distance above the ends 28-29 of the outer walls 25, as shown, so that when the letter is secured to the base board 11, that the outer faces will hold tightly to the base board and prevent rain or moisture from getting thereunder. Of course it is understood that letters like O, P, R, Q and A will be composed of two pieces in the cast letters; but in all other respects the letter will correspond to other letters in this class. In fact, it will ⁷⁵ not be noticed where the two pieces are connected so as to form such letters. But in the pressed sheet metal letters each will be composed of a single piece as shown.

With this style of pressed letter, it may or ⁸⁰ may not be provided with sockets for lamps used in these illuminated signs, or as has been explained in connection with Fig. 6, the letter may be used with the neon tube or any other form of illuminating means. As shown, this ⁸⁵ style of letter is fastened to the base 11 by a washer 30 and a screw 31.

Characters of this class, be they letters or numerals, may be used for any purposes desired. Besides using them on sign boards for display purposes, they may be used for placing the name of a person or the title of the company on the building, whether or not it be wood, cement or stone. By the use of the letters and numerals, as described herein, a ⁹⁰ varied use may be made with them, at a cost of about one-third the cost of the less durable style, as at present. Again, at present, as noted, the letters and other characters are each cut out of sheet metal fitted and soldered ⁹⁵ to a base by an experienced operator. No change can be made, and the sign is scrapped at the end; no part of it can be used for other purposes.

Of course, it will be understood that in ¹⁰⁰ the pressed characters, a suitable anchor will be provided attached to the letter, whereby the same may be placed on a suitable base.

With the letters and other characters made as above described, each of which will be ¹⁰⁵ made in various sizes to meet the demands, it will be readily seen how easily and quickly an elaborate sign may be made up, and if the various characters are painted as noted, the same may be made very artistic, all at a very ¹¹⁰ much reduced cost as compared with such signs as are made up and used for general advertising sign purposes.

While I have herein described the form of my invention as at present preferred and which I consider to represent the best embodiment thereof, yet I desire to have it understood that the various forms shown are only illustrative and that the invention may be carried out in other ways than that shown ¹¹⁵ ¹²⁰ ¹²⁵ ¹³⁰

and described; for instance, the making of such characters by casting or pressing the same up from sheet metal, with or without a trough therein, as may be desired, each style 5 adapted to be used separately or may be combined with others to form acceptable combinations.

Having fully described my invention, what I claim as new and desire to secure by Letters Patent of the United States is:

A device of the character described comprising a metallic body including a pair of spaced upwardly extending flange members, a base portion disposed between and interconnecting the lowermost ends of said flange members, thereby forming an intermediate depressed channel between said flange members adapted to house a source of light, said base portion extending the whole width of 15 said body, the outer walls of said flange members being downwardly and outwardly inclined, the inner walls of said flange members being downwardly and inwardly inclined, and fastening means incorporated in the 20 lowermost thickened portions of said flange members while the latter are in a plastic state.

In testimony whereof I affix my signature.
RUDOLPH T. KELLER.
